UNITED STATES PATENT OFFICE.

RICHMOND M. McGEE, OF DALLAS, TEXAS, ASSIGNOR TO McGEE SWITCH & SIGNAL COMPANY, OF DALLAS, TEXAS, A CORPORATION OF TEXAS.

ELECTRIC RAILWAY-GATE.

No. 886,842.

Specification of Letters Patent.

Patented May 5, 1908.

Application filed August 8, 1907. Serial No. 287,673.

To ~~all~~ whom it may concern:

Be it known that I, RICHMOND M. McGEE, a citizen of the United States, residing at Dallas, county of Dallas, State of Texas, have invented certain new and useful Improvements in Electric Railway-Gates; and I do hereby declare the following to be a full, clear, and exact description of the invention, such as will enable others skilled in the art to 10 which it appertains to make and use the same.

The object of the invention is to provide an electrically actuated railway crossing gate having switch mechanism for reversing the 15 motor circuit at approximately the limit of movement of the gate in either direction, electro-magnetic means for independently actuating the switch mechanism to arrest the movement of the gate in either direction, together with means carried by the gate arm which, upon striking an obstacle in its descent, arrests the movement of the gate and places the operating apparatus in condition to immediately reverse the gate movement, 20 the operations of raising, lowering and reversing the respective movements of the gate being conveniently controlled by an operator located in a tower or other suitable station. These and other objects of the invention will 25 appear more particularly in the annexed specification, considered in connection with the accompanying drawings, in which:

Figure 1 is a side elevation of a gate and its operating mechanism, the casing inclosing 30 the mechanism being shown in section; Fig. 2 is an end view of the apparatus shown in Fig. 1, the casing being shown in section; Fig. 3 is a detail of the electric switch for arresting the gate when the same descends upon an obstacle on the track; and Fig. 4 is a diagrammatic view of the electric circuits and the apparatus connected therewith.

Referring to the drawings, 1 indicates the 45 pivoted arm of a railway crossing gate, which may be of any preferred or convenient form, and is connected to a transverse shaft 3 mounted in a suitable stand or casing 100. Where the gate is adapted to be used in connection with a roadway and a foot-path or 50 sidewalk as well, there is provided a secondary gate 2 connected to a shaft 4, as will be well understood by those skilled in the art.

The apparatus for raising and lowering the 55 gate consists of an electric motor 60, preferably of the shunt type, upon the shaft 5, of

which is mounted a gear 6 which is connected by means of a gear train 7, 8, 9 and 9' with a segmental gear 10, which latter is provided with an arm 11 carrying at its end a pin 12 which engages a slot 14 in bell-crank 13 which is secured to the shaft of the gate 1, and causes the latter to rise or fall as the motor 60 is rotated in one direction or the other. In order to swing the auxiliary or sidewalk gate 2 concurrently with the main gate, the latter 65 is connected to the bell-crank 13 by means of a link 15 and crank-arm 16, which latter is secured to the shaft of said gate 2.

The current for operating the motor 60 may be derived from any convenient source, 70 such as a power transmission line, which may supply a number of gates, or, in case the gate is in isolated position, from a suitable battery. The illustration indicates a battery 80 for supplying the current to the motor and 75 the subsidiary apparatus of the gate.

As indicated the invention contemplates the provision of means for breaking the motor circuit when the gate has reached either limit of its movement, and, at the 80 same time, reversing the motor current, preferably, by reversing the contacts of the shunt field circuit, so that when the motor circuit is again closed the motor will operate in a reverse direction to produce a corresponding 85 movement of the gate.

In order to effect the shifting of the pole changer by the operation of the gate, there is provided a rock lever 18 loosely mounted upon the shaft of the segment 10, and provided with pins 19 and 20 which are adapted to engage the sides of arm 11 of the segment, as the gate reaches its lower and upper limits, respectively, by means of which engagement lever 18 is rocked, thereby actuating the 90 movable member of the pole changer 23 in one direction or the other by means of lever-arm 21, connected to said lever 18, and link 22 which connects said arm 21 with the movable member of said pole changer, as clearly 95 illustrated in Figs. 1 and 2.

The pole changer may be of any appropriate form, but is conveniently constructed as shown in the drawings, consisting of a reciprocating bar 59 carrying suitable bridge-pieces or contacts 61, 62 and 63, said bridge-piece 61 serving to alternately connect fixed contact members 42 and 43, and 44 and 45; bridge-piece 62 serving a similar purpose with respect to fixed contacts 40 and 41, 110

and 46 and 47; and bridge-piece 63 operating alternately to connect fixed contacts 53 and 54, and 55 and 56. As thus far explained, it will be understood that the electrical part of the apparatus may be rendered effective by closing appropriate circuits in any manner, either by means of a manual circuit controller actuated by an operator near the gate or at a distance therefrom, or by suitable track circuits, automatically closed to lower the gate as the train approaches the crossing, and similarly closed by the train as it passes beyond the crossing to raise the gate. In order to effectively and absolutely control the movement of the gate in either direction, that is to say, to completely lower or raise the same, to arrest its movement at any point, and to reverse the movement after it has been so arrested, there is provided electrical means for operating the pole changer 23 independently of the movement of the gate. Said means consists of two opposite electro-magnets 57 and 58, which are preferably solenoids located on opposite sides of the pole changer, having their cores formed as extensions of, or connected with the bar 59 which constitutes the main movable member of the pole changer. Inasmuch as the mechanical operation of the pole changer by means of segment 10 and rock lever 18 is effected at approximately the limit of the movement of the gate in either direction, namely, by the engagement of sides of arm 11 of segment 10 with pins 19 and 20, respectively, of rock lever 18 as the segment 10 approaches the limits of its movement in either direction, it will be apparent that said rock lever is free to be moved in the opposite direction from that in which it has been moved by segment 10, as soon as the gate begins its opposite movement. For example, in Fig. 1, which shows the gate in lowered position with segment 10 and its connected gearing ready to be operated by the motor to raise the gate, the movable members of the pole changer are in engagement with the lower sets of fixed contacts. If, after the motor has been started solenoid 57 be energized, it will be apparent that it will lift bar 59 and change the movable contacts of the pole changer into engagement with the upper sets of fixed contacts, thereby reversing the field of the motor independently of the movement of the gate. Should the gate be in its opposite position or in any intermediate position, it will be noted that solenoid 58, when energized will shift the movable member of the pole changer to reverse the field of the motor.

To effect the operation of the motor in either direction and also to actuate solenoids 57 and 58, when found necessary or desirable, the arrangement of the circuits shown in Fig. 4 may be conveniently employed, said circuits being controlled by the pole changer 23, aforesaid, and a manual switch 70 oper-

ated by the gate tender. The condition of the circuits shown in Fig. 4 is that when the gate is in raised position. When the gate is to be lowered, switch 70 is moved to contact 75 which closes the circuit from battery 80 through switch 70, contact 75, lead 84 to contact 53, bridge-piece 63 of the pole changer, fixed contact 54, connector 81, lead 83 to one brush of the motor through the armature to lead 81, and back to the battery by way of lead 81. From the armature of the motor the current divides, part passing through the field by way of lead 85 and connector 49, fixed contact 40, bridge-piece 62, fixed contact 41, cross-connector 52, fixed contact 45, lead 79 through the field, lead 78 to fixed contact 46, cross-connector 51, fixed contact 42, bridge-piece 61, fixed contact 43, leads 86, 87 and 81 back to the battery 80. When the motor has completely lowered the gates, bar 59 has shifted the movable member of the pole changer 23, so that the bridge-pieces thereon engage the opposite sets of fixed contacts and the circuit of the motor is broken between contacts 53 and 54. When it is desired to raise the gate switch-arm 70 is moved to contact 72, thereby establishing the following circuit which drives the motor in the reverse direction: battery 80, switch-arm 70, contact 72, lead 88, fixed contacts 55, bridge-piece 63, fixed contacts 56, cross-connector 81, lead 83 through the armature of the motor and back to the battery by way of lead 81. The current through the field, however, takes the following course: from lead 81 outside the motor brushes by way of lead 85 to cross-connector 49, stationary contact 47, bridge-piece 62, stationary contact 46, lead 78, through the field, in the opposite direction to that heretofore described, lead 79, fixed contact 45, bridge-piece 61, fixed contact 44, cross-connector 48, leads 86, 87 and 81 back to the battery. As soon as the gate has been lowered the pole changer will be mechanically operated, as hereinbefore described, to again operate the pole changer to break the circuit of the motor at contacts 55 and 56 and move bridge-pieces 61 and 62 again in position to reverse the field of the motor.

Should it be found desirable to stop the movement of the gate at any position, it will only be necessary to break the corresponding circuit by means of switch 70. On the other hand, should it be found desirable to stop the gate in its movement in either direction and immediately reverse the same, the operations may likewise be effected by means of the proper actuation of switch 70. In order to reverse the movement of the gate, it will first be necessary to shift the pole changer 23. If switch 70 be moved to contact 74 while the gate is being lowered, the first effect of the movement of the switch will be to break the circuit to the motor, which effects the

lowering of the gate, and to arrest the movement of the latter as the switch arm passes between contacts 75 and 74. As soon as the arm 70 engages contact 74, it closes a circuit 5 from battery 80 through the switch arm contact 74, lead 96, through solenoid 58, through cross-connector 89, back to the battery by way of lead 81. The energization of solenoid 58 shifts the pole changer 23 to the opposite 10 position of that shown, thereby reversing the current through the field of the motor. To raise the gate from the intermediate position at which it had been stopped in its downward movement, switch arm 70 is shifted 15 into engagement with stationary contact 72 which closes the circuit, heretofore explained, through the motor to effect the desired operation. Similarly, when it is desired to arrest the gate in its upward movement and immediately reverse the same, switch arm 70 is moved into engagement with contact 71 which closes a circuit in battery 80 through switch-arm 70, contact 71, lead 90, solenoid 57, leads 91 and 81, back to 20 the battery which energizes said solenoid 57 and shifts the pole changer so that the motor field will be reversed. To lower the gate from the position in which it had been stopped, it is only necessary to move switch 25 arm 70 into engagement with stationary contact 75 which closes the circuit through the motor, heretofore described, to effect this operation.

In order to check the movement of the 30 motor, as soon as its circuit has been disrupted, a suitable brake may be provided. This brake may be of any preferred form and it may, if desired, be automatic in its operation, being applied when the motor circuit is 35 off and released when the motor circuit is on. A simple and convenient form of brake, however, is illustrated in the drawings, in which

10 represents a brake-applying solenoid, to the core of which is connected lever 112, on 40 the outer end of which is mounted brake-shoe 111, which engages a disk 114 on the motor shaft. Normally the brake is retracted by a suitable spring 113, but when it is desired to apply the brake, switch-arm 70 45 is moved into engagement with stationary contact 73 which closes the circuit from battery 80 through solenoid 110, as follows: switch-arm 70, contact 73, lead 99 through the solenoid 110, lead 99', and back to the 50 battery by way of lead 81.

It frequently happens that a vehicle, animal or other obstacle is caught below the descending gate with the consequent danger of being caught upon the tracks. In anticipation of any such contingency special means are provided, whereby, when the gate in its 55 lowering movement comes in contact with any object, the movement of the gate will be immediately arrested and then reversed to clear the object and prevent the same from

being caught under the gate. To effect this purpose, there is stretched between the end of the gate arm 1 and a suitable pulley 31 a rope or cable 30, the other end of which is attached by a stout spring, sufficiently strong 70 to keep the cable taut, secured to the gate near its pivotal point. The spring is attached to the cable by means of a rod 33 adapted to reciprocate in a suitable guide 38 mounted on the inside of the gate arm. 75 Mounted upon said rod 33 is a bridging contact 36 which is adapted to engage fixed contacts 34 and 35 on the guide 38, when the cable 30 has been pulled upon striking a wagon or other object. Normally, however, the contact 36 is held out of engagement with contacts 34 and 35 by spring 37 which holds the cable taut, as clearly indicated in Fig. 3. When contact 36 has been moved into engagement with contacts 34 80 and 35 by the engagement of cable 30 with some object below the gate, a circuit is closed from a battery 93 by way of lead 92, contact 35, bridging contact 36, contact 34, lead 92, solenoid 58, lead 96, lead 96' through an 85 auxiliary solenoid 95, back to the battery 93. The effect of this operation is first to cause solenoid 58 to shift pole changer 23 to a position to reverse the field of the motor for the purpose of raising the gates. Simultaneously therewith solenoid 95 is energized and retracts its core 97, the end of which is provided with a hook which engages switch-arm 70 and shifts the same into engagement with fixed contact 72, which closes the circuit 100 through the motor and starts the same to raise the gate. As soon as the obstacle has been cleared, spring 37 draws the cable taut and moves contact 36 out of engagement with contacts 34 and 35 thereby breaking 105 the circuit through solenoid 95. The upward movement of the gate, however, continues until arrested by the manipulation of switch 70 by the operator, or until the circuit of the motor is automatically broken by 110 the mechanical shifting of the pole changer as the gate reaches its upward position.

The mechanism for operating the gate is designed with a special view of effecting an easy and positive movement of the gate in 115 both directions, the motor which actuates the gate attaining substantially its full torque before the gate begins to move in either direction and the initial movement of the gate in either direction being relatively 120 slow, the speed of movement increasing until the gate has traveled approximately one-half of its course and the speed then decreasing regularly until it stops. Under these circumstances the gate starts and stops without 125 any appreciable jar or shock and its absolute control is assured. These peculiar features of the operation are due primarily to the reducing gearing connecting the motor 60 with the actuating segment 10, and the connection of 130

the latter with the bell-crank 13 by means of pin 12 and slot 14. It will be noted that, by reason of the relation of pin and slot 12 and 14, the initial movement of the gate in either direction is comparatively slow because of the angular disposition of the engaging arms of bell-crank 13 and segment 10. As these engaging arms approach alinement, the speed of the movement of the gate increases and after the arms aforesaid pass out of alinement and begin to assume an angular relation on the opposite side of the dead center, the speed of movement of the gate gradually decreases.

15. What I claim is as follows:

1. In a railway crossing gate, the combination of the pivoted gate arm, an electric motor for raising and lowering said arm, gearing connecting said arm with the motor, 20 switch mechanism for changing the poles of the motor circuit operated at approximately the limit of movement of the gate in either direction, and electro-magnetic means for independently actuating the switch mechanism.

2. In a railway crossing gate, the combination of the pivoted gate arm, an electric motor for raising and lowering said arm, gearing connecting said arm with the motor, 30 switch mechanism for changing the poles of the motor circuit operated by the motor at approximately the limit of movement of the gate in either direction, electro-magnets for independently operating the switch mechanism and circuit controlling means for operating said electro-magnets.

3. In a railway crossing gate, the combination of the pivoted gate arm, an electric motor for raising and lowering said arm, 40 gearing connecting said arm with the motor, a pole changing switch in the motor circuit operated by the motor at approximately the limit of movement of the gate in either direction, oppositely disposed electro-magnets 45 for actuating the pole changing switch independently of the motor, a manual switch, and circuits connecting the same with the electro-magnets for operating the pole changing switch to arrest the movement of the gate in either direction.

4. In a railway crossing gate, the combination of the pivoted gate arm, an electric motor for raising and lowering said arm, 50 gearing connecting said arm with the motor, a pole changing switch in the motor circuit operated by the motor at approximately the limit of movement of the gate in either direction, oppositely disposed electro-magnets for actuating the pole changing switch independently of the motor, a manual switch, circuits

connecting the same with the electro-magnets for operating the pole changing switch to arrest the movement of the gate in either direction, and additional circuits between said manual switch and the motor adapted 65 to be closed by the said manual switch to reverse the operation of said motor.

5. In a railway crossing gate, the combination of the pivoted gate arm, an electric motor for raising and lowering said arm, a 70 pole changing switch in the motor circuit operated by the motor at approximately the limit of movement of the gate in either direction, and means carried by the gate adapted to be actuated upon striking an object during 75 the descent of the gate to arrest the movement of the motor.

6. In a railway crossing gate, the combination of the pivoted gate arm, an electric motor for raising and lowering said arm, a 80 pole changing switch in the motor circuit operated by the motor at approximately the limit of movement of the gate in either direction, electro-magnets for actuating the pole changing switch independently of the motor 85 circuits including a manual switch for said electro-magnets, a yielding-device on the gate to engage any obstacle below said gate, a circuit closer connected with said yielding device including the magnet for shifting the 90 pole changer to position for raising the gate, and an electro-magnet for moving the manual switch to close the circuit to the motor to effect the raising operation.

7. In a railway crossing gate, the combination of the pivoted gate arm, a prime mover for raising and lowering said arm, 95 gearing connecting said primary mover with the gate arm including a bell-crank connected with the gate, and a pin and slot connection 100 between said bell-crank and the connecting gearing.

8. In a railway crossing gate, the combination of a pivoted gate arm, a motor for raising and lowering said arm, reducing gear- 105 connecting said motor with the gate arm, said gearing comprising an oscillatory segment, a bell-crank connected with the gate, and a pin and slot connection between said bell-crank and segment, the engaging arms 110 of the bell-crank and segment being angularly disposed with respect to each other when the gate is in either its upper or lower position.

In testimony whereof I affix my signature, 115 in presence of two witnesses.
